[57] ABSTRACT

An improved electronic alarm watch is disclosed having improvements in the structure and arrangement of the acoustically alarming vibrator employed in the alarm mechanism thereof. The improved watch of the above type comprises a watch casing, wherein is located a watch movement, alarm switch controlled thereby, alarm oscillator circuit and a battery source adapted for energization thereof. An oscillatory membrane is fixedly attached with a piezo-electric or electrostrictive element which is electrically connected through the switch with the oscillator circuit and the battery for being energized therefrom, the membrane being arranged in a space defined by and between a perforated back cover and the watch movement.

WATCH WITH ELECTRONIC BUZZER

BACKGROUND OF THE INVENTION

This invention relates to improvements in and relating to electronic alarm watches; more specifically, it is concerned with improvements in the structure and arrangement of the acoustically alarming vibrator of the alarm mechanism employed in such watches.

Various and numerous mechanical alarms have been broadly used in the field of alarm watches. It is, however, a grave drawback that the mechanical alarm conventionally used operates substantially at a rather lower frequency field than about 1,000 cycles per second, thus representing a rather low loudness level in comparison with a substantial amount of the fed energy for the alarm service. Although consumers are nowadays acquainted with tones of electronic sense, especially with the pitch and timber thereof, by virtue of rapidly developing and broadly marketed electronic time-pieces, the mechanical alarm can not meet with such modern demands by consumers. A further drawback inherent in the conventional mechanically alarmed watches resides in a gradual attenuation of the loudness during continued service of the alarm device, thus generally speaking, substantially no effective alarming caution being felt by the watch bearer during the latter half of the alarm service. With such mechanical alarm, the watch bearer must wind up the power spring of the alarm device almost every time after a practical service of the device. In addition, sounds of variable tone sense can not be delivered from the mechanical alarm device, because it delivers only a monotonous acoustic alarm signal.

In consideration of the above conventional drawbacks inherent in mechanical alarm devices, it has already been proposed to fit an electronically operated buzzer energized by current from a battery.

Almost all prior electronic alarms for use with watches are, however, designed and arranged to be of the electrodynamic type employing coils and permanent magnets cooperating therewith, resulting in a substantially large sized device, especially large dimensions for the buzzer-operating circuit and the acoustic converter. In the conventional arrangement of the above-kind, the watch movement and the electronic buzzer are arranged generally in a common plane and parallel to each other, thus the overall assembly has larger outer dimensions than otherwise; frequently a certain irregular outline configuration must be employed, disturbing thereby the desired appearance and compactness of the watch assembly including the alarm device. In addition, provision of the permanent magnet means provides disadvantageous effect upon the time base vibrator and thus, there are problems which require to be solved.

In the conventional arrangement the watch movement and electronic buzzer in parallel to each other in a common plane, they must be encased in separate compartments for attaining a satisfactory sealed structure, because it is highly difficult to arrange these two main structural units together in a circle, in addition the vibrator or the like acoustically alarming member must be arranged in physical contact with the ambient atmosphere, so as to perform an efficient acoustic alarming function. Such an arrangement will naturally have a highly complex overall structure and the number of the related parts must be increased which pro-

duces in turn a corresponding increased manufacturing cost.

SUMMARY OF THE INVENTION

It is therefore a main object of the invention to provide an electronically alarmed compact watch having substantially the same outline dimensions as other conventional watches of the water-proof structure, with all the necessary components of the alarm device arranged in a self-contained mode.

For this purpose, the invention starts from a substantially conventional watch which comprises a watch casing, wherein is located a watch movement, alarm switch controlled thereby, alarm oscillator circuit and a source battery adapted for energization thereof.

According to the main feature of the present invention, a membrane is fixedly attached with a piezoelectric or electro-strictive element electrically connected through said switch with said oscillation circuit and said

20 battery for being energized therefrom, said membrane being arranged in a space defined by and between a perforated back cover and the watch movement. The membrane, together with said piezo-electric or electro-strictive element and a membrane carrier, is electrically so connected with the alarm oscillator circuit as to be easily detachable therefrom, and thus equally with the watch unit. The membrane is preferably made of a conductive metal foil. However, when necessary, it can be made from a plastic film or sheet. In this case, the electric connection is made directly with the element, thus without the intermediary of the membrane per se.

BRIEF DESCRIPTION OF THE DRAWINGS

These and further objects, features and advantages of the invention will become more apparent from the following detailed description of the invention with reference to the accompanying drawings illustrative of several preferred embodiments of the invention.

40 FIG. 1 is an axial sectional view of a preferred first embodiment of the invention, substantially taken along a section line I-I' shown in FIG. 2, wherein, however, an alarm oscillator circuit block is only partially sectioned and a main movement block and a battery block are shown only in their outline configuration.

45 FIG. 2 is a bottom plan view of the watch unit shown in FIG. 1 wherein, however, the back cover and the oscillatory membrane are broken away for display of inner working parts.

50 FIG. 3 is part of a perspective view of the alarm oscillator membrane attached fixedly with an electro-strictive element, said membrane being shown as mounted at its periphery by a membrane carrier formed in this embodiment into a ring.

55 FIG. 4 is a schematic and illustrative view, demonstrating the power transmission mode as well as the electric connection mode among several main working parts employed in the foregoing first embodiment of the invention.

60 FIG. 5 is a schematic plan view, shown on a reduced scale, of the watch movement employed in the foregoing first embodiment and taken out from the watch unit shown in FIGS. 1 and 2.

65 FIG. 6 is substantially similar view to FIG. 1, illustrating, however, a second embodiment of the invention and demonstrating those which are different from those shown therein.

FIG. 7 is part of an axially sectional view of a preferred third embodiment of the invention, shown, however, in a substantially similar way to FIG. 1, yet on a somewhat enlarged scale.

FIG. 8 is a similar view to FIG. 7, showing, however, a preferred fourth embodiment of the invention.

FIG. 9 is a part of a perspective view of a back cover employed in the fourth embodiment shown in FIG. 8, wherein, however, said back cover is sectioned partially.

DETAILED DESCRIPTION OF PREFERRED EMBODIMENTS

Referring now to FIGS. 1-5, the first embodiment will be described hereinbelow in detail.

Numeral 1 generally denotes a watch movement in its broadest sense and comprises a conventional pillar plate 2, appearing only partially and mounting several main working parts, as will become more clear as the description proceeds.

Numeral 3 represents a mercury battery of known structure and detachably mounted within said movement 1. In the present embodiment, this battery 3 is adapted to feed an electronically operated timepiece movement and a buzzer with current, as will be more specifically described hereinafter.

A battery mount 4 made of an insulating material and fixed with said pillar plate 2 mounts the battery block 3 in position, a pressure spring 5 detachably attached by means of set screw 5a and 5b to the plate 2 holding the battery block in position from upper of FIG. 1 with a slight resilient pressure applied thereto.

Numeral 6 represents only schematically an electronic drive circuit of conventional structure and molded into a block with a synthetic resin and detachably attached to pillar plate 2 by means of set screws 6a, 6b and 6c. This drive circuit is adapted for driving electro-dynamically a conventional time base oscillator, preferably in the form of a balance wheel motor, a turning fork, a turning lead or the like, as commonly known per se. The drive circuit is electrically connected through the plate 2 and lead wire means, not shown, to the battery 3, as known per se.

Numeral 8 represents a main working parts block including the conventional watch gear train and comprising a balance wheel 8a which is driven electromagnetically from said electronic drive circuit 6, said gear train, although not shown specifically by virtue of its very popularity, being mounted by and between the plate 2 and bridges 8e; 8f which is fixedly attached thereto by means of a plurality of set screws 8b; 8c and 8d. It should be mentioned at this stage that the term "block" in this case is used only for convenience so as to discriminate the gear train as a whole from other working parts of the watch and it does not constitute a practical block.

Numeral 9 represents an alarm oscillator circuit block comprising transistor(s), condenser(s), resistors and the like which constitute an electronic oscillator and compacted into a molded block 9a by a synthetic resin such as an epoxy base resin, and a transformer 9b electrically connected with said oscillator and with a piezo-electric or electro-strictive element 25. This transformer 9b serves for elevating the output from the oscillator in its voltage so as to adapt for oscillation of the element 25 as will become more apparent as the description proceeds. This circuit block 9 is fixedly, yet

4
easily detachably attached to the plate 2 by means of several set screws 9c; 9d.

Numeral 10 denotes a conventional time-indicating dial bearing on its outer surface with known time-indicating symbols although not shown, for the demonstration of time by cooperation with time-indicating hands 14, 15 and 16. This dial 10 is detachably mounted on the plate 2, although the attaching means have been omitted from the drawing only for simplicity and convenience. It should be noted, however, that a conductive strip 10a is provided in a concentric ring on the inside surface of the dial 10, and preferably, by the print circuit technique.

Battery mount plate 4 is formed with a perforation 4b in which a U-shaped contact spring 4a is kept in position in somewhat projecting manner. In the assembled position shown, this contact spring 4a serves as conducting means between said battery 3 and conductive strip 10a.

Numeral 11 denotes a conventional cannon wheel and a conventional unlocking wheel 12 is rotatably mounted thereon. An unlocking spring 13 is provided as shown, especially in FIG. 1, the root end of this spring 13 is fixedly mounted on a terminal 9e of said oscillator circuit block 9 by means of a set screw 13a. The free end 13b of spring 13 is kept in pressure contact with the upper surface of the wheel 11, so as to urge resiliently the latter to move axially downwards when seen in FIG. 1. A projection or contact portion 13c is formed on the spring 13 at an intermediate point between the ends thereof, thus providing a possibility to establish an electrical cooperation with conductive strip 10a on the dial 10. In this way, an unlocking switch 30 (FIG. 4) is constituted by the combination of cannon wheel 11, unlocking wheel 12 and unlocking spring 13.

Cannon wheel 11 is formed with three projections 11a having mutually different radial lengths measured from the center of the wheel 11. Only for simplicity, however, these projections 11a is represented as if they are single in FIG. 1. In a corresponding way, unlocking wheel 12 is formed with three different perforations 12a which are, however, represented as only one as a representative thereof for simplicity.

Although not shown, there is provided a conventional alarm time setting device manually operable by a main winding stem 40, or alternatively by an auxiliary second stem, not shown, as the case may be, for setting the unlocking wheel 12 to a desired alarm time. For indication of the alarm time, the unlocking wheel 12 is fitted with alarm hand 14. This hand 14 is press-fit on the boss of the wheel 12.

As commonly known, the cannon wheel 11 performs a complete revolution per 12 hours by receiving motion from the gear train of the watch. When the alarm time comes, the projectons 11a on the wheel 11 are brought into engagement with corresponding and mating perforations and 12a on the wheel 12, thereby the former wheel 11 being urged to move downwards in FIG. 1 and nearer towards the latter wheel 12, so as to establish an electrical connection between the contact portion 13c on spring contact 13 and the conductive strip 10a on dial 10.

Hour hand 15 is press-fit on the boss of cannon wheel 11 as conventionally. Minute hand 16 is attached on top of a conventional cannon pinion 17.

Numeral 18 represents a case central body which mounts detachably a transparent plastic cover 19 used in this specific embodiment in place of a crystal, a ring-shaped tension spring 19a urging the cover from inside to expand resiliently outwards, so as to establish a tight and sealed connection between the cover and the case center body.

A ring-shaped movement positioner 20 is positioned along its substantial peripheral length between plate 2 and case central body 18. A sealing ring 21 is inserted between the case central body 18, and a membrane carrier 22 having a ring web projection 22a on which the periphery of a oscillatory membrane 24 is fixedly attached by means of adhesive. The carrier 22 is formed with an inwardly projecting arm 22b and provided with an insulator sleeve 23a which holds firmly a combined stationary contact and terminal 23. On the inside surface of the membrane 24, a piezo-electric or electrostrictive element 25 is firmly attached by glueing or the like conventional attaching means, a conductive lead 26 connecting electrically the contact and terminal 23 with the element 25.

The molded alarm oscillator circuit block 9 is provided at its output side with a conductive spring arm 9f which is normally kept in pressure and conductive contact with the member 23 when the block 9 and membrane carrier 22 have been assembled together in position as seen clearly from FIG. 1. The root end of said spring arm 9f is embedded rigidly in the mass of the molded block 9.

Membrane carrier 22 is formed at its periphery with an outwardly extending positioner projection 22c which is kept in engagement with an inwardly directing recess 18b formed on case center body 18. In the assembled position shown in FIGS. 1 and 2 and thus, under the engaging position of these positioning means 18b; 22c, the spring arm 9f is kept in pressure contact with the matching contact and terminal 23 as above referred to.

In the first embodiment so far shown and described, the oscillatory membrane 24 is made of aluminum foil having a thickness of about 50 - 100 microns and glued to the upper surface of ring stem 22a as was referred to briefly hereinbefore, yet in a conductive way therebetween. In order to realize such conductive attachment, the glueing agent per se may be made conductive in such a way that pulverized carbon is mixed with the agent. Or alternatively, the membrane is subjected to a high axially compressive pressure upon glueing thereof to the carrier, even when the glueing agent per se is of non-conducting nature. The element 25 is glued to the inner surface of the membrane, preferably at its center as shown, so as to establish an electric connection therebetween.

When the element 25 is made piezo-electric, it is prepared by way of example from Rochelle Salt, ammonium hydrogen phosphate, lithium sulphate, dipotassium tartrate. On the other hand, when the element is made electro-strictive, it is prepared by way of example from barium titanate, $PbZrTiO_3$ or the like. Consequently, the element 25 comprises a substrate 25a consisting of anyone of the aforementioned materials and having electrodes 25b; 25c deposited on both surfaces. In the present embodiment, one electrode 25b is glued to the membrane 24 as briefly referred to hereinbefore, while the remaining electrode 25c is fused to the end

of lead 26. This mode is more specifically seen from FIG. 3.

Numeral 27 denotes a back cover which is formed with a number of projections 27a over its substantial whole area so as to prevent a tight contact with the wearer's skin, while the remaining base area 27b is formed with a number of perforations 27c for releasing acoustic alarming signals from inside of the watch in the open atmosphere.

At the outside periphery, the back cover 27 is formed with several recesses 27d for receiving operating end of a turning tool. Further, the back cover 27 is formed on its peripheral surface with male screw threads 27 adapted for engagement with mating female screw threads 18a formed on the case central body 18. For attachment of the back cover 27, it is screwed from upper into the body 18 by use of the turning tool.

It will be clear from the foregoing that the interior space of the watch as defined by membrane 24, carrier 22 thereof, sealing ring 21, case central body 18 and transparent and plastic front cover 19 is kept effectively in a sealed condition for prevention of the invasion of moisture from outside into the inside of the watch. It should be noted in the present specific embodiment that the oscillatory membrane 24 acts as a means of seal by defining means for providing the aforementioned sealed-in chamber which preserves the main working constituents including the watch movement in an effectively sealed way.

As an example, if it is assumed that the membrane 24 is made of aluminum having a thickness of 50 microns, then a sealed-off condition of the said sealed chamber under a static pressure corresponding to about 10-meter depth in water is assured. The normally required waterproof requirement can be satisfied by use of such an alarm watch structure.

The operation of the first embodiment of the watch alarm according to the first embodiment of the present invention will be described in detail, additionally by reference to FIG. 4.

The unlocking wheel 12 is set to a certain selected time point by manipulating the main or auxiliary winding stem, as was briefly described hereinbefore.

Current is fed from battery 3 through several conductive parts to electronic drive circuit 6. More specifically, the positive side of battery 3 is connected through pressure spring 5, pillar plate 2 and a certain conductor, not shown, to the positive inlet terminal, not shown, of the drive circuit 6. On the other hand, the negative side of battery 3 is connected spring 4a, conductive strip 10a and a certain conductor, not shown, to the negative inlet terminal, not shown, of the drive circuit 6, as conventionally. In this way, the watch gear train, not shown, is driven and cannon wheel 11 is caused to rotate continuously as briefly referred to hereinbefore.

When the alarming time comes, projections 11a on the wheel 11 are brought into engagement with corresponding perforations 12a in the wheel 12 so that the former wheel 11 is urged to move downwards in FIG. 1 under the action of unlocking spring 13 and the intermediate contact portion 13c thereof is brought into pressure contact with the conductive strip 10a, thereby the unlocking switch 30 being turned to on. In this way, current is supplied from battery 3 to alarm oscillator circuit 9. More specifically, a circuit is closed through battery 3, contact spring 4a, conductive strip 10a on

dial 10, unlocking spring 13, oscillator circuit 9 and pillar plate 2.

When the oscillator circuit 9 starts to oscillate in this way at a certain constant frequency, preferably selected between 1,000 and 3,000 cycles per second, the oscillatory output voltage therefrom is conveyed through the elevating transformer 9b to the element 25 which is thus kept in oscillation together with its carrying membrane 24. Practically, the transformer 9b constitutes a member of the circuit 9 and serves for transmitting the oscillative electric drive energy from the oscillator circuit to the element 25. By the oscillative movement of the membrane 24, a corresponding acoustic signal is generated and will be delivered from the interior of the watch casing comprising the members 18, 19 and 27 into the open atmosphere through the perforations 27c of the back cover 27.

Next, the second embodiment of the invention will be described hereinbelow by reference to FIG. 6.

In this embodiment, same or similar parts to those which have been employed in the foregoing embodiment are denoted with respective same reference numerals added each with 100, for easy comparison and understanding and regardless of occasionally appearing minor configurational difference.

In this embodiment, the watch movement is of the similar structure and arrangement as before. A spring arm 109f acting as a contact or terminal is equally provided for the alarm oscillator circuit block 109 and embedded in the molded mass by its root end as before. 118 denotes a case central body, 120 a movement positioner and 121 a sealing ring. Membrane carrier 122 of a conductive material is formed substantially into a circular disc which is, however, formed with a ring projection 122a at a proximity to the outer periphery of the disc, said ring projection being formed with a number of radially directing, preferably equally spaced radial openings 122c acting similarly as the perforations 127c for the delivery of the acoustic alarm signal. A contact piece 123 is mounted fixedly in an insulator sleeve 123a which is firmly held in the circular disc portion of said carrier 122 at a position corresponding to the acting end of the spring arm 109f. The oscillatory membrane 124 is glued at its peripheral area to the upper surface of the ring projection 122a in a conductive way as before. The membrane 124 is attached firmly, preferably at its center, with a piezo-electric or electrostrictive element 125 by glueing in a conductive way as before, said element being electrically connected through a lead 126 with the contact piece 123 again as before.

Numerical 127 represents back cover which is formed with male threads 127e at its outer periphery for screw fitting thereof with the mating female threads 118a of case central body 118. This back cover 127 is formed further with a number of radial openings 127c adapted for release of alarming sound signals.

Water-proofness of the watch is attained by the combination of membrane carrier 122, sealing ring 121, case central body 118 and a plastic or glass cover which may be similar to that shown at 19 in the first embodiment, although not shown. Therefore, it will be seen from the foregoing description that in the present embodiment, the membrane 124 has nothing to do with the realization of the water-proofness contrary to that shown at 24 in the first embodiment.

Since the membrane 124 is exposed at its both surfaces to the ambient atmosphere, it will not be sub-

jected to destructive stresses by the occasionally and substantially increased ambient pressure, such as in deep water.

Next, referring to FIG. 7, the third embodiment of the invention will be described hereinbelow in detail.

In this embodiment, same or similar parts as those employed in the first embodiment are denoted with respective same reference numerals, each, however, being added with 200 for easy identification and comparison, regardless of occasional minor configurational difference.

Numerical 208 represents a main working parts block containing the regular watch gear train. This block 208 does not constitute a real block, as was referred to similarly in the first embodiment and the nomination of the "block" is only for the convenience of description and graphical representation. Numerical 210 represents a dial, 209 an alarm oscillator circuit block, having a spring arm 209f, the root end of which is firmly embedded in the molded mass of the block. Numerical 218 denotes the case central body and 221 represents a sealing ring. The back cover 227 is formed with a number of sounds releasing perforations 227c, although only one thereof is shown as a representative.

25 The back cover 227 is formed on its inside wall surface with a ring shoulder 227f to which the oscillatory membrane 224 carrying the piezo-electric or electrostrictive element 225 is glued firmly at its peripheral zone.

30 An auxiliary inside cover 222 is pressed-on or glued to the inside wall of the back cover, so as to define a chamber in which the membrane 224 is contained as shown. On the inside or lower surface of the inside cover 222, a conductive strip 223 is fixedly attached by glueing or the like conventional fixing means at a position substantially in registration with the conductive spring arm 209f. A lead 226 connects electrically the spring arm 209f with the piezo-electric or electrostrictive element 225 as before. For this purpose, the lead 226 passes through a perforation 222d drilled through the inside cover 222 which is made of an insulating material such as plastic, rubber or the like.

35 40 45 A fixing screw ring 228 is provided for fixedly attaching the back cover 227 to the case central body 218, said ring 228 being formed for this purpose with male threads 228a adapted for screw engagement with corresponding female threads 218a on the body 218. The ring 228 is provided with a plurality of recesses 228b, only one thereof being shown in FIG. 7 as a representative thereof for simplicity, adapted for engagement with a turning tool, not shown.

50 55 Water-proofness of the watch is assured by the combination of membrane 224, back cover 227, sealing ring 221, case central body 218 and a glass or plastic cover or crystal, not shown.

The reason for the provision of screw ring 228 for attachment of back cover 227 to the case body 218 is for assuring the predetermined registration of the both conductive members 209f and 223 and for the prevention of unintentional turning of the back cover relative to the case body, or more specifically to the conductive spring arm 209f.

60 65 Finally, referring to FIGS. 8 and 9, the fourth embodiment of the invention will be described hereinbelow in detail.

In this embodiment, same or similar parts as employed in the first embodiment are denoted with re-

spective same reference numerals, each being, however, added with 300 for easy comparison, irrespective of occasional minor configurational difference.

The oscillatory membrane 324 fitted tightly with a piezo-electric or an electro-strictive element 325 is attached tightly at its peripheral zone to a shoulder 327f formed on the inside wall surface of a perforated back cover 327; an inside cover 322 made of an insulating material and fitted with a conductive strip 323 is press-fit from inside onto the back cover 327. The element 325 and the conductive strip 323 is connected electrically by means of a conducting lead 326 which passes through a perforation 322d drilled through the inside cover.

The back cover 327 is formed with a large concentric opening 327h and with a plurality of radical recesses 327g.

A secondary and auxiliary back cover element 331 is press-fit into the said concentric opening 327h. For prevention of occasional and unintentional disengagement of the cover element 331 from the mating and receiving opening 327h, the element 331 is formed with an enlarged and resilient end ring 331a acting as a kind of stop means. The overall diameter of the cover element 331 is so selected that the latter does not cover in any appreciable degree and that these recesses 329g act well for release of alarming sounds from inside of the watch unit into the open atmosphere therethrough, when such sounds are generated by oscillatory movement of the membrane 324.

Numeral 321b represents a sealing ring for keeping of a sealing connection between the members 320 and 327. A further sealing ring 321a is provided for keeping a sealed connection between the members 318 and 327.

It should be noted that in the present embodiment, the conductive strip 323 is formed into a concentric ring relative to the back cover 327, thus no specifically selected registration being unnecessary to establish an electric connection between the both conductive members 323 and 309f. Thanks to this specific structure, the back cover 327 per se is formed with male threads 327e for screw coupling with the case central body 318.

Water-proofness is assured by the combination of oscillatory membrane 324, back cover 327, sealing ring 321a, case central body 318 and a glass or plastic cover or crystal, not shown.

After establishment the electrical connection through the conducting lead 326 as in the aforementioned way, the passage opening 322d can be filled up with a certain filler material such as plastic resin, so as to maintain the water-tightness by the help of inside cover 322, should the membrane 324 be broken by occasional and unintentional application of an appreciably high pressure onto the membrane. This feature can also be applied to the third embodiment shown in FIG. 7.

The reason for the provision of the auxiliary back cover element 331 is to provide a possibility for cleaning and removal of dirty particles invaded from outside through said recesses 327g into the membrane-containing space of the watch unit and after provisional removal of the back cover element 331.

In the third and fourth embodiments, different from the first and second embodiments, the back cover attached with the membrane can be treated as a sub-unit in the assembly of the watch unit. Therefore, it will be

seen that the assembly job can be performed substantially similarly with the case of a non-alarmed watch unit.

In any of the foregoing embodiments, the membrane and its carrier could be arranged in a substantially proximate position with each other as for preventing excess distortion of the membrane when unintentional high pressure is occasionally applied thereto.

When the oscillatory membrane is made of a plastic film or sheet, both electrodes of the piezo-electric or electrostrictive element are connected electrically through respective conductor leads with two contacts mounted or on the inside cover, as the case may be, and the input and output terminal of the alarm oscillator circuit are electrically connected with the said two stationary contacts.

Similar connecting mode can be employed for the electrodes of the oscillatingly drive element and the terminals of the alarm oscillator circuit, as will be easily understood from the foregoing, when the back cover or the auxiliary back cover element is made of an insulating material such as plastics.

The embodiments of the invention in which an exclusive property or privilege is claimed are as follows:

1. In a watch with an electronically driven alarm, the watch comprising in combination, a watch casing with a watch movement contained therein, an alarm switch controlled thereby, an electronic alarm oscillator circuit contained within said casing and a source battery adapted for energization of said oscillator circuit and contained within said casing, the alarm comprising an oscillatory membrane and a piezo-electric or electrostrictive element fixedly attached to said membrane and electrically connected through said switch with said oscillator circuit and said battery for being energized therefrom, said membrane being arranged in a space defined by and between a perforated back cover and the watch movement and tightly supported at its peripheral area on a membrane carrier which is arranged between said back cover and said watch movement.

2. Alarm watch as set forth in claim 1 wherein said membrane, together with said piezo-electric or electrostrictive element and a membrane carrier, is electrically so connected with the alarm oscillator circuit as to be easily detachable therefrom, and thus equally from the watch unit.

3. Alarm watch as set forth in claim 1, wherein said membrane is made of a conductive metal foil.

4. Alarm watch as set forth in claim 1 wherein said membrane carrier acts as a part of water-proofing members of the watch unit.

5. Alarm watch as set forth in claim 1, wherein said back cover is formed with a number of projections for prevention of a tight contact with human skin.

6. Alarm watch as set forth in claim 1, wherein said membrane acts as a part of water-proofing members of the watch unit.

7. Alarm watch as set forth in claim 6, wherein the membrane and its carrier or an inside cover member are arranged substantially in proximate position with each other as for preventing excess distortion of the membrane when unintentional high pressure be applied thereto.

8. In a watch with an electronically driven alarm, the watch comprising in combination of a watch casing, a watch movement contained therein, an alarm switch

controlled thereby, an electronic alarm oscillator circuit contained within said casing, and a source battery adapted for energization of said oscillator circuit and contained within said casing, the alarm comprising an oscillatory membrane and a piezo-electric or electrostrictive element fixedly attached to said membrane and electrically connected through said switch with said oscillation circuit and said battery for being energized therefrom, said membrane being arranged in a space defined by and between a perforated back cover and the watch movement and fixedly mounted at its peripheral zone by said back cover which is provided with a contact terminal connected through a lead with said element.

9. Alarm watch as set forth in claim 8, wherein said membrane, together with said piezo-electric or electrostrictive element and a membrane carrier, is electrically so connected with the alarm oscillator circuit as to be easily detachable therefrom, and thus equally from the watch unit.

10. Alarm watch as set forth in claim 8, wherein said membrane is made of a conductive metal foil.

11. Alarm watch as set forth in claim 8, wherein said membrane carrier acts as a part of water-proofing members of the watch unit.

12. Alarm watch as set forth in claim 8, wherein said back cover is formed with a number of projections for prevention of a tight contact with human skin.

13. Alarm watch as set forth in claim 8, wherein said membrane acts as a part of water-proofing members of the watch unit.

14. Alarm watch as set forth in claim 13, wherein the membrane and its carrier or an inside cover member are arranged substantially in proximate position with

each other as for preventing excess distortion of the membrane when unintentional high pressure be applied thereto.

15. In a watch with an electronically driven alarm, the watch comprising in combination of a watch casing, a watch movement contained therein, an alarm switch controlled thereby, an electronic alarm oscillator circuit contained within said casing, and a source battery adapted for energization of said oscillator circuit and contained within said casing, the alarm comprising an oscillatory membrane and a piezo-electric or electrostrictive element fixedly attached to said membrane and electrically connected through said switch with said oscillation circuit and said battery for being energized therefrom, said membrane being arranged in a space defined by and between a perforated back cover and the watch movement and made of a conductive metal foil, said element comprising a pair of electrodes and said watch being characterized by that one of said electrodes is conductively connected with said membrane.

16. Alarm watch as set forth in claim 15, wherein said back cover is formed with a number of projections for prevention of a tight contact with human skin.

17. Alarm watch as set forth in claim 15, wherein said membrane acts as a part of water-proofing members of the watch unit.

18. Alarm watch as as set forth in claim 17, wherein the membrane and its carrier or an inside cover member are arranged substantially in proximate position with each other as for preventing excess distortion of the membrane when unintentional high pressure be applied thereto.
